UNITED STATES PATENT OFFICE.

CHARLES ADAMS-RANDALL, OF NEW YORK, N. Y.

TELEPHONE-TRANSMITTER.

No. 913,931.

Specification of Letters Patent.

Patented March 2, 1909.

Application filed April 14, 1905. Serial No. 255,602.

To all whom it may concern:

Be it known that I, CHARLES ADAMS-RANDALL, a citizen of the United States, residing at New York, in the county of New York and State of New York, have invented new and useful Improvements in Telephone-Transmitters, of which the following is a specification.

This invention relates to telephone transmitters or apparatus for the electrical transmission of speech, and more especially to that class of transmitters adapted for use with "common battery systems" and currents of high potential, with means for regulating and obtaining the proper resistance thereof, proportioned to the current employed, and the circuit used therewith, and also embodying means in combination for obtaining and varying the required normal resistance for the transmission of articulate speech and other sounds.

The object of the invention is to produce a transmitter of novel construction having a high resistance without impairment of the variability of the resistance medium and adapted more especially for the transmission of speech by the use of currents of higher voltage than usually employed with battery transmitters, such as regulated electric light currents, without detriment to the transmitter, and in a manner more economical and effective than by the use of dry batteries or electric currents of low voltage, as now generally practiced.

In the drawings, Figure 1 is a plan view of a part of the transmitter. Fig. 2 is a sectional elevation of the same. Fig. 3 is a plan view of the transmitter embodying a modification. Figs. 4, 5, 6 and 7 illustrate plan views of different forms of pads having elongated openings therein for containing the resistance granules and coöperating with the diaphragm, these pads being modifications of the granule holding means shown in the preceding figures.

Similar characters of reference are employed to indicate corresponding parts in the several views.

The numeral 1 designates the body or casing of the transmitter which may be of any suitable material and has an upper section disposed thereon, as particularly shown by Figs. 2 and 3. The body or casing 1 carries a diaphragm 3, which rests upon a ring 4 of rubber, paper or other suitable material, the

diaphragm being held in place by any preferred means. The improved transmitter embodies the principle of increasing the normal internal resistance thereof and directly controlling said resistance without liability of "packing" of the resistance granules and without impairment of the variability of the latter, and thus materially increase the effectiveness of a granule resistance means in telephone transmitters.

Referring particularly to Figs. 1 and 2, the variable resistance consists in granules of carbon or other suitable material G. The granules are contained in an annular recess 25, formed in a felt or other analogous pad 26, held against the diaphragm 3 by any suitable means, the said recess 25 constituting a cell, seat or pocket of extended length, preferably of narrow width and shallow depth and in which the granules are thinly spread over the given area and separated at diametrically opposite points by insulating bridges 27, of vulcanite or analogous material. The pad 26^a, as shown by Fig. 4, is substantially similar to the pad 26, and may be substituted for the latter, and instead of using the insulating bridge 27 the material of the pad is continued at diametrically opposite points, as at 26^b, to divide the pocket or seat for the carbon granules G into independent segmental members or parts. In Fig. 5, the pad 26^c has but a single connecting web 26^d between the inner and outer portions thereof and the electrical contact is made with the carbon granules in the pocket, cell or seat therefor in this form of pad through the medium of suitable devices located at the ends P, P' of the pocket, but, by preference, the electrical contacting or connecting means with respect to the granules will be of a form hereinafter specifically referred to and shown by Fig. 2, and in the instance where a switch is used, and which will be explained in connection with Fig. 3. In Fig. 6, the pad 27^a is further modified by preserving the main portion thereof intact or imperforate and forming a diametric slot 27^b therein to serve as a pocket or cell means for the retention of the resistance granules, contact with the granules being established at the ends of said slot. The pad 28^a shown by Fig. 7 is still further varied as to form a slot 28^b, which, in this instance, is continuous almost entirely throughout the full body width by forming a series of communicating oblong

openings intersected by intermediate partitions 28^e. This materially elongated pocket or cell to receive the resistance granules provides for the use of a larger quantity of the 5 granules with increased resistance and freedom from "packing", and in this form of the transmitter by the movement of the granules by the operation or vibrations of the diaphragm a far greater variation of the variable 10 resistance is obtained than is possible when the granules are held in a deep receptacle. The electrical contact with the granules in the pocket or cell, as constructed in the pad shown by Fig. 7, will be established at the 15 diagonally opposed terminals of the slot; as indicated at P, P'.

The construction shown by Figs. 1 and 2 and the portions of the pads having elongated openings for holding resistance granules, as shown by Figs. 3, 4, 5, 6 and 7, embody the principle of increasing the internal 20 resistance of the transmitter by obtaining the variable resistance in a thin, elongated or extended area, in contradistinction to an increased depth of granules, whereby the liability of "packing" by the resistance granules is overcome, thus materially increasing the effectiveness and variability of the granular resistance means in telephone 25 transmitters, and at the same time increasing the normal resistance and the total resistance when two or more separate, disconnected, independent variable resistances are used by connecting the same in circuit, in series by 30 suitable means.

One of the preferred means of making contact with the granules at the ends of the pocket or cell in its various forms, as just set forth, and also for connecting the granules 40 in the pockets in circuit, in series, is shown by Figs. 2 and 3. This preferred connecting means consists of metal bolts 28, 29, 30 and 31, secured to the non-metallic or insulating frame 2 of the transmitter by 45 means of nuts 28^d, a second nut 28^e being provided on each bolt for securing the wires or other connections to the several bolts. Each bolt is provided with a flat or thin head 23, which rests upon and covers the granules 50 at the ends of the pockets and makes electrical contact with the said granules, as shown by Fig. 2, and owing to this arrangement the cover must pass through or over the granules from one end of the pocket to the other end, 55 the shaking up, disturbing, or vibrating the granules by the variations of the diaphragm producing a variation in the resistance offered to the current passing therethrough or thereover. As shown by Fig. 3, 60 two of the bolts, for instance 29 and 31, are connected by wires 34 and 35, with terminals 36 and 37, and extending also from the bolt 37 to a suitable switch point 38 on the member 2 by a connecting wire 39. A second 65 switch point 40 is also secured on the member

2 in proper position and is connected by a wire 41 with the bolt 30. A switch arm 32 is movably supported on the member or pad 2 of the transmitter, and has its fulcrumed end connected by a wire 42 with the bolt 28. 70 This switch arm 32 is shiftable between the contacts 38 and 40, and may be drawn over on to either one of the latter to connect the different sets of separate, independent, disconnected variable resistances severally, in 75 series, to graduate the resistance of the transmitter to the required amount, and by which means the resistance of the transmitter is regulated. In other words, the movement of the switch arm 32 to the contact 38 cuts 80 out the materials or granules in one of the pockets from the circuit, while moving the switch arm to the contact 40 places said resistance material in both pockets in series in the circuit. 85

Although a non-metallic diaphragm has thus far been described as being preferred to render the transmitter more effective in its operation, it will be understood that the improved transmitter is not limited to the 90 use of a non-metallic diaphragm, as a metal diaphragm may be used, which may have the granules insulated therefrom.

In granular telephone transmitters of normally high resistance it has been customary 95 to obtain the normal variable resistance by the use of specially high resistance carbon granules arranged in a cup or receptacle having an increased depth to contain a greater mass of granules than ordinarily 100 used. This has been found objectionable in that the granules when so arranged do not permit of a great or ready variation of the resistance, and they are also more liable to "pack" when the variation becomes slight 105 or very nearly *nil*. By the construction heretofore described and embodied in this invention, the granules are held in an elongated pocket, cell, seat, groove or recess, and are disposed over a greater, increased or 110 lengthened area of proper dimensions and are thinly spread, in contradistinction to the deep pocket or cup, so that the current passes over and through the granules in the direction of their length, or in the direction of 115 the length of the cell or pocket, the surface covered generally determining the normal resistance in the pocket. By this particular arrangement a maximum variation of the 120 granules is readily obtained from the vibration of the diaphragm or other vibrator actuating them, and hence the said granules are not likely to "pack", and also permits the use of a comparatively high voltage current, especially when several variable resistances 125 are connected up in circuit, in series. It will also be understood from the disclosure as to variation and shape of the pockets, as well as separation of the latter, that any number of the pockets may be used and so 130

connected up in series as to obtain the normal internal resistance desired, and it is also intended to adopt various other forms of pockets or cells and variable electrodes or resistances without departing from the general scope of the invention, and which is to provide a transmitter having means for readily obtaining and regulating the resistance, and of varying the said resistance for the transmission of articulate speech electrically when using a current of much higher voltage than now generally used.

Having thus described the invention, what is claimed, is:

1. A telephonic transmitter having an elongated receptacle means of narrow width and shallow depth, and a granular variable resistance in the said receptacle means, the resistance of the said variable granular resistance being in the direction of its length in contradistinction to its depth.

2. A telephone transmitter characterized by having elongated receptacle means of narrow width and shallow depth, and a granular variable resistance disposed in said receptacle means for increasing the normal internal resistance of the transmitter, the parts being so arranged that the current passes over or through the variable resistance in the direction of its length in contradistinction to its depth.

3. A telephone transmitter having therein two or more independent, disconnected, elongated receptacles, granular variable resistance material disposed in the receptacles, and independent means for connecting up the latter.

4. A telephone transmitter having a plurality of separate, disconnected, elongated receptacles, granular variable resistance material disposed in said receptacles, and independent means for connecting up the variable resistance material in the receptacles in circuit, in series.

5. A telephone transmitter having separate, independent, electrically disconnected, elongated variable resistances of shallow depth, the said resistances being arranged in separate receptacles and the current passing lengthwise over and through the resistances, and means for electrically connecting the resistances serially for the purpose of increasing

the internal resistance of the transmitter, the said connecting means being independent.

6. A telephone transmitter characterized by having separate, disconnected, independent variable resistances held in elongated receptacles in which the total resistance is determined by the length of the receptacles and variable resistance over which the current must pass, and means for connecting the variable resistances in circuit, in series, the receptacles being of shallow depth.

7. A telephone transmitter having a diaphragm or vibrator, a plurality of independent granular resistances carried thereby and insulated therefrom and from each other, the resistance of the granules being in the direction of the length of the mass of the same, contact means engaging the granular resistances at the extreme ends of the extended mass of granules, and means for connecting said independent granular resistances in circuit, in series, with each other, and a source of electric energy.

8. A telephone transmitter, having a diaphragm and vibrator, and a plurality of elongated receptacles containing resistance granules, the granules being insulated from the diaphragm, and independent means for connecting two or more elongated receptacles in series with means for connecting such receptacles at their extreme ends to obtain an increased resistance according to the length and in contradistinction to the depth of the receptacle.

9. Means for increasing the normal internal resistance of a telephone transmitter, consisting in arranging variable granular resistance material over an elongated area and having such material of shallow depth, the current passing solely over and through the resistance material in the direction of the length of said material, whereby the resistance of the material is increased without affecting its variability.

In testimony whereof I have hereunto set my hand in presence of two subscribing witnesses.
